UNITED STATES PATENT OFFICE.

MONTGOMERY DAKIN, OF LESLIE, MICHIGAN.

NECK-YOKE.

SPECIFICATION forming part of Letters Patent No. 294,447, dated March 4, 1884.

Application filed July 12, 1883. (No model.)

To all whom it may concern:

Be it known that I, MONTGOMERY DAKIN, a citizen of the United States of America, residing at Leslie, in the county of Ingham and State of Michigan, have invented certain new and useful Improvements in Neck-Yokes and Whiffletrrees, of which the following is a specification, reference being had therein to the accompanying drawings.

10 My invention relates to neck-yokes; and it consists in the parts which will be hereinafter described, and pointed out in the claims.

In the accompanying drawings, Figure 1 represents a perspective view of a neck-yoke 15 provided with my improvement. Fig. 2 is a central cross-section. Fig. 3 is a partial longitudinal section. Fig. 4 is a plan view of the truss-plates as used on a carriage or a buggy pole, said plates being provided with 20 depressions to admit yoke-straps to pass under them.

Like letters indicate like parts in the views. A is the whiffletree.

25 B B are two truss-plates secured to the whiffletree. These truss plates lap at the center of the neck-yoke, and they are provided with end hooks, B' B'.

C C are ferrules provided with the offset C' C'. The hook ends of the truss-plates are 30 secured to the ferrules. Said ends lie within the depressions on the under side of the projections C', and the ends B' lap over said projections, thereby securing the ferrules, which will be more fully hereinafter specified.

35 D is a ring provided with a depression, D', and a right-angled twist, D².

E is a cap-plate provided with a curved part, E'. In the part E' a groove, E², is formed, to admit the curved part D' of the 40 ring. The under ring, D², is adapted to receive the ends of the pole.

45 F is a plate on the upper part of the whiffle-tree. Said plate is provided with an enlarged part, F', the part F' having a groove, F², therein to admit the ring. G G are bolts, which pass through the two upper plates, thence through the neck-yoke, and then through the lapped ends of the truss-plates.

G' are nuts on said bolts.

H H are depressions in the plates to admit 50 the yoke-strap on carriage or buggy harness.

The truss-plates serve a twofold purpose—they strengthen the neck-yoke and secure the ferrules.

The appliances may be attached to a whiffle-tree without departing from the spirit of my invention. When so used, the truss-plates would form a rub-iron to prevent the wheel 55 from wearing the whiffletree.

It will be observed that by the arrangement 60 of parts as shown a farmer can easily iron a yoke without mechanical assistance. The lower ring in carriage or buggy yokes is to be wound with leather through, beginning at top and winding to top, where both ends are secured with twisted wire. The lower ring of carriage or buggy yokes may be covered with leather and stretched thereto properly, having hole for reception of pole. This leather 65 of course prevents wear on end of pole.

70 By having the depression or curve D' in the ring said ring conforms to the upper plates and prevents the yoke from revolving in the ring.

Having thus described my invention, I claim 75 as new and desire to secure by Letters Patent—

1. In a neck-yoke or whiffletree, truss-plates provided with end hooks, and ferrules having offset to admit the plates, as specified, in combination with bolts whereby said plates are secured to the whiffletree, substantially as set forth.

2. The plates E and F, having the depressions adapted to receive the ring D, as specified, in combination with the ring D, having 85 the depression D' and right-angled twist D², substantially as described, and for the purpose set forth.

In testimony whereof I affix my signature in presence of two witnesses.

MONTGOMERY DAKIN.
